[57] CLAIM

The ornamental design for a golf ball dispenser, as shown and described.

DESCRIPTION

FIG. 1 is a perspective view of golf ball dispenser for practicing golf showing my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a sectional elevational view thereof.

The broken lines in FIG. 1 indicate environment only and form no part of my design.

FIG.1**FIG.2**

FIG. 3

FIG. 4

FIG. 5

FIG. 6

FIG. 7
